CLAIM

The ornamental design for a retail furnishings group, as shown and described.

DESCRIPTIONFIG. 1 is a front perspective view of a retail furnishings group showing our new design;
FIG. 2 is a left side view thereof;
FIG. 3 is a right side view thereof;
FIG. 4 is a front view thereof;

FIG. 5 is a rear view thereof; and,
FIG. 6 is a top view thereof.

The broken lines in the figures show portions of the retail furnishings group that form no part of the claimed design.

1 Claim, 6 Drawing Sheets
